Patented Apr. 5, 1921.

INVENTOR
Frederick M. Furber

UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BLACKING-MACHINE.

1,373,497.

Specification of Letters Patent.

Patented Apr. 5, 1921.

Application filed January 22, 1917. Serial No. 143,799.

To all whom it may concern:

Be it known that I, FREDERICK M. FURBER, a citizen of the United States, residing at Revere, in the county of Suffolk and State 5 of Massachusetts, have invented certain Improvements in Blacking-Machines, of which the following description, in connection with the accompanying drawings, is a specification, like reference characters on the 10 drawings indicating like parts in the several figures.

This invention relates to machines for use in finishing boots and shoes and particularly to machines for applying blacking, 15 stain, sizing or other finishing material, herein referred to generically as blacking, to shoe parts such, for example, as the edges and rands of the heels or soles of boots and shoes.

20 A general object of the invention is to devise a machine for applying blacking quickly and neatly to shoe parts, particularly to both the edge and rand of a shoe sole. Machines of this type commonly comprise a rotatable edge blacking device together with a device which acts as a combined rand crease guide and rand blacking means and also serves as a guard to protect the upper. Preferably the rand blacking 25 means and edge blacking means in such machines are mounted for relative displacement in order that the machine may accommodate itself to different types of shoes in which there is a varying depth of rand 30 crease. Blacking is commonly supplied continuously during the use of the machine and in case of interruption of work, the blacking may accumulate in considerable quantities so as to interfere with the proper operation of the machine when work is again 35 applied thereto.

With a view to avoiding the difficulty above discussed, features of the invention consist in a machine organization in which 40 the flow of blacking to one or both of the blacking devices is controlled by relative displacement of the blacking devices. In the illustrated machine the application of work to operative position relative to the 45 machine controls the flow of blacking.

50 Another feature of the invention consists in the provision of a machine especially designed for blacking the edges and rands of shoe soles in which both the rand and

the edge blacking means are positively rotated to insure a proper supply of blacking, the construction and arrangement being such that one of the blacking devices may be displaced from its normal axis of rotation, the blacking supplying means being 60 so related to the displaceable blacking means that the relative displacement of the two means controls the flow of blacking.

Still another feature of the invention consists in a particular arrangement of a stirrer 65 within a blacking receptacle to the end that the driving shaft for the stirrer may pass through the bottom of the receptacle without the necessity for a packed joint.

The preferred construction of such a machine will be described in the following 70 specification taken in connection with the accompanying drawings, in which,

Figure 1 is a side elevation, partly in section, of my improved machine; and 75

Fig. 2 is a perspective, partly in section, of the rand blacking means.

Bolted to the column 10 is a frame 12 in which is journaled a shaft 14 which is adapted to be connected to the driving 80 pulley 16 by the operation of a clutch lever 18 which, in the particular arrangement shown, comprises cam surfaces 20 for engaging the clutch members 22 against the tension of the spring 24.

85 Mounted on the upper end of this frame 12 is a blacking receptacle 26 provided with a cover 28 and with a stirrer 30, constructed as a spider with depending arms, which is bolted to the upper end of a shaft 32 journaled in the frame 12 and passing through a sleeve 34 rising upward from the base of the receptacle and preferably constructed integrally therewith. The height of the sleeve is greater than the normal depth of 90 the blacking in the receptacle and therefore constitutes an effective arrangement for preventing leakage and at the same time avoids the necessity of any kind of a stuffing box around the shaft 32. A worm 36 upon the 100 shaft 14 cooperates with a gear 38 to drive the stirrer shaft 32.

A sleeve 40 formed in a bracket 42 upon the frame 12 serves as a bearing for a hollow shaft 44 which is positioned in the 105 sleeve by means of a collar 46 and a worm gear 48. This gear meshes with a worm 50 mounted on the shaft 14 and serves as

means for driving the hollow shaft to which the gear is attached by means of a screw 52. The gear 48 is formed with a sleeve extension 54 which is screw-threaded at its upper 5 end to serve as an attaching means for the edge blacking brush 56. This brush is constructed with a perforated circular guide 58 between the rows of bristles to prevent their depression within a fixed periphery. 10 At the same time the perforations in this guide allow the flow of blacking from one row of bristles to the next.

Arranged concentrically with the edge blacking brush is a frusto-conical combined 15 rand crease guide and rand blacking means 60. This rand blacking device is preferably constructed in the manner more clearly shown in Fig. 2, from which it will be seen that a chamber 62 is provided within the 20 rand blacking device. This chamber communicates with one base of the frustum, here the upper surface, by means of an annular groove or opening 64 and with the other base by perforations 66. The device 25 is preferably provided with bristles 68 mounted in a wall of the chamber 62 and within a recess within the lower base of the guide and interposed between the perforations 66. Thus the perforated wall of the 30 chamber may be said to constitute the back of the brush. This rand blacking device is mounted on a shaft 70 within the hollow shaft 44 and mechanically connected for simultaneous rotation therewith by means of 35 a universal joint 72 by reason of which relative movement of the edge blacking and rand blacking means is allowed. The hollow shaft 44 is constructed with a conical socket 74 on its interior which co-operates 40 with a ball-shaped member 76 slidably mounted upon the shaft 70 and pressed into the socket by a spring 78. This latter arrangement tends to move the two blacking devices into concentric relation but does not 45 interfere with their relative displacement upon the application of work.

A nozzle 80 is pivotally mounted in a bracket 82 formed on the receptacle 26 and is provided with a channel 84 connected to 50 the receptacle 26 by means of a flexible tube 86. A thumb screw 88 allows for regulation of the size of the channel 84 thereby to control the flow of blacking. The nozzle is held in engagement with the upper surface of the 55 rand blacking device 60 by means of a spring 90. Preferably, the upper surface of the rand blacking device 60 is slightly spherical and the lower surface of the nozzle is correspondingly recessed in order that the 60 nozzle may be held in close contact with the upper surface of the rand blacker and prevent leakage of blacking. The opening in the lower end of the nozzle is so designed that it may be closed by the end surface of 65 hub 92 of the rand blacking device when the

same is centrally related thereto. As soon, however, as the rand blacking device is displaced laterally or from concentric relation with the nozzle 80 and the edge blacking brush 56, there will be a flow of blacking 70 through the annular groove 64 into the chamber 62 and thence through the perforations 66 and the perforations in the guide 58 to all parts of the rand blacking device and the edge blacking brush. 75

The edge of the sole will be presented to the blacking machine in the manner indicated in Fig. 1 so that the sharp edge of the rand blacking device 60 enters the rand crease. The work is then still further advanced until the edge of the sole contacts with the edge blacking brush 56 with a resulting relative displacement of the two thus causing a flow of blacking through the annular groove 64 to the two blacking devices. 80 No blacking is delivered to the upper surface of the rand blacking device 60, however, and this arrangement also serves as a guard to prevent soiling the upper. The guide 58 in the brush 56 prevents too great a depression 85 of the bristles of the brush 56 by the application of work. It will be noted that by means of this arrangement, blacking is supplied only at the time of the application of work and it is immediately shut off upon the removal of the work by reason of the action of the spring-pressed ball 76 in returning the rand blacking device 60 to its central position. The volume of flow may effectively be controlled by manipulation of the thumb 90 screw 88. During the operation of the machine the blacking in the receptacle 26 is constantly adjusted by rotation of the stirrer 30.

While I have herein described this machine particularly with reference to its use 105 in applying blacking to the rand and edge of a shoe sole, it will be understood that it may readily be applied to other parts of a shoe and its use is not limited to this particular application. 110

Having thus described my invention, what I claim as new and desire to secure by Letters Patent of the United States is:—

1. A blacking machine having, in combination, a driven rand blacking means, driven edge blacking means, said means being mounted for relative movement, means for supplying said means with blacking, and means operated by the relative movement of said blacking means to control the delivery 115 of blacking thereto. 120

2. A blacking machine having, in combination, driven edge blacking means, driven rand blacking means mounted for relative yielding movement by the work, means for 125 supplying blacking to said blacking means, and a valve controlled by the relative position of the rand and edge blacking means to govern the supply of blacking thereto.

3. In a blacking machine, driven edge 130

- blacking means, driven rand blacking means arranged for rotation concentrically with the edge blacking means and constructed and arranged so that it may be displaced relatively thereto, means tending to restore the concentric relation of said means, and means for supplying blacking to the blacking means. 5
4. In a blacking machine, rotatable edge blacking means, rotatable rand blacking means, and means for driving one of said blacking means, said blacking means being mechanically connected for simultaneous rotation but arranged so that one of said blacking means may be displaced relative 10 to the other upon the application of work.
5. In a blacking machine, a blacking receptacle, a rotatable blacking brush, and means for supplying blacking from the receptacle to said brush through the interior 15 thereof, comprising a collecting chamber in the brush for the blacking, one wall of the chamber constituting the back of the brush in which its fibers are mounted, and being provided with perforations for the passage 20 of the blacking to the fibers.
6. In a blacking machine, a rotatable blacking means, means for driving said blacking means arranged to allow displacement of the same relative to its normal axis 25 of rotation, and means for supplying blacking to said blacking means while the same is rotating, said supplying means being constructed and arranged so that the flow of blacking is controlled by the displacement 30 thereof from its normal position.
7. In a blacking machine, driven rotatable edge blacking means, and rotatable rand blacking means mechanically connected therewith and normally extending beyond 35 the periphery of said edge blacking means, said mechanical connection being arranged to allow relative displacement of said blacking means whereby upon the application of work the rand blacking means may be 40 moved to accommodate it to varying depths of rand crease.
8. In a blacking machine, rotatable edge blacking means, rotatable rand blacking means, a universal joint connection between 45 said blacking means arranged to allow relative displacement during simultaneous rotation, means including a spring for holding said blacking means normally in concentric relation, means connected to one of said blacking means for driving both of said blacking means, and means for supplying blacking to the blacking means. 50
9. In a blacking machine, a rotatable edge blacking brush mounted on a hollow shaft, a rotatable rand guide and rand blacking means mounted on a shaft within said hollow shaft and connected thereto at a point remote from the blacking means, by a universal joint, a socket within said hollow 55
- shaft, a spring-pressed member on said inner shaft co-operating with the socket tending to maintain the blacking devices in concentric relation, means for driving the hollow shaft, and means for supplying blacking to the blacking means. 65
10. In a blacking machine, a rotatable combined rand guide and rand blacking means comprising a hollow frusto-conical device provided with an annular groove in one base and perforations communicating with the other base, and a blacking nozzle held against the base which is provided with an annular groove and normally closed by said device but adapted to be put in communication with the annular groove by the displacement thereof upon the application of work. 70
11. In a blacking machine, a blacking receptacle, a stirrer member having downwardly extending arms, a shaft for driving said stirrer leading through the base of said receptacle, a bearing for said shaft comprising a sleeve tightly joined with the base of said receptacle and extending to a point above the level of the liquid therein, and means for withdrawing and utilizing the blacking at a point below the upper end of the sleeve. 75
12. In a blacking machine, means for applying blacking to the sole of a shoe comprising a brush having therein a chamber for blacking, means for supplying blacking to said chamber comprising a nozzle, said nozzle and applying means being relatively movable laterally with respect to said applying means, means for yieldably forcing the nozzle and applying means into engagement, and means operating during the lateral movement for automatically controlling the flow of blacking through the nozzle. 80
13. In a blacking machine, means for applying blacking to the sole of a shoe comprising relatively movable members one of which has a chamber for blacking, means for supplying blacking to said chamber comprising a valve, and means for controlling said valve by contact of the shoe with one of the members. 85
14. In a blacking machine, means for applying blacking to the sole of a shoe comprising a brush having therein a chamber for blacking, means for supplying blacking to the chamber comprising a nozzle member held in contact with one surface of the brush with the nozzle opening communicating with the chamber, and means operable through the contact of the work with the brush for controlling automatically the supply of blacking to said chamber. 90
15. In a blacking machine, means for applying blacking to the sole of a shoe comprising a brush having therein a chamber for blacking and an opening leading into 95
- 100
- 105
- 110
- 115
- 120

the chamber, means for supplying blacking to the brush comprising a nozzle the opening in which is over the opening into the chamber when the shoe is properly engaged 5 with the brush, and means for automatically displacing the openings relatively to each other so that the opening in the nozzle is closed when the shoe is removed.

16. In a blacking machine, means for applying blacking to the sole of a shoe comprising a rotary brush having therein a chamber for blacking and an opening leading into the chamber, means for supplying blacking to the brush comprising a nozzle 10 held yieldingly against the brush with the opening in the nozzle over the opening into the chamber while the shoe is being operated on, and means for automatically moving the brush to shut off the supply for 15 blacking thereto when the shoe is removed.

17. A blacking machine having, in combination, a driven rand blacking means, driven edge blacking means, said means being mounted for relative movement, means 20 for supplying said means with blacking, and means operated by the relative movement of said blacking means to control the delivery of blacking to one of the blacking means.

30 18. A blacking machine having, in combination, means for blacking one part of a shoe, means for blacking another part of a

shoe, said means being mounted for relative movement, means for supplying said means with blacking, and means operated by the 35 relative movement of said blacking means to control the delivery of blacking thereto.

19. A blacking machine having, in combination, means for blacking one part of a shoe, means for blacking another part of a 40 shoe, said means being mounted for relative movement, means for supplying said means with blacking, and means operated by the relative movement of said blacking means to control the delivery of blacking to 45 one of the blacking means.

20. In a blacking machine, plural rotatable blacking means, means for driving said blacking means arranged to allow for their relative movement under the control of 50 the work in the hands of the workman, and means for supplying blacking to the blacking means, the construction and arrangement being such that movement of a blacking means controls the flow of blacking. 55

21. In a blacking machine, a rotatable blacking means, and rotatable means for supplying blacking to the blacking means, the construction and arrangement being such that displacement of the supplying 60 means controls the flow of blacking.

In testimony whereof I have signed my name to this specification.

FREDERICK M. FURBER.
